US0D1044900S

(12) **United States Design Patent** (10) Patent No.: **US D1,044,900 S**
(45) Date of Patent: ** Oct. 1, 2024

(54) **WAREHOUSING ROBOT**

(71) Applicant: **HAI ROBOTICS CO., LTD.**,
Guangdong (CN)

(72) Inventors: **Shaokai Zhuo**, Guangdong (CN);
Qiqiang He, Guangdong (CN)

(73) Assignee: **HAI ROBOTICS CO., LTD.**,
Guangdong (CN)

(**) Term: **15 Years**

(21) Appl. No.: **29/838,532**

(22) Filed: **May 13, 2022**

(30) **Foreign Application Priority Data**

Nov. 19, 2021 (CN) 202130766461.0

(51) **LOC (14) Cl.** **15-99**

(74) Attorney, Agent, or Firm — Frank Gao, Esq.

(57) **CLAIM**

The ornamental design for a warehousing robot, as shown and described.

DESCRIPTION

FIG. 1 is a first perspective view of a warehousing robot; FIG. 2 is a second perspective view thereof; FIG. 3 is a third perspective view thereof; FIG. 4 is a front view thereof; FIG. 5 is a rear view thereof; FIG. 6 is a left view thereof; FIG. 7 is a right view thereof; FIG. 8 is a top view thereof; FIG. 9 is a bottom view thereof; FIG. 10 is a detail view of the encircled portion on FIG. 1; FIG. 11 is a detail view of the encircled portion on FIG. 1; FIG. 12 is a detail view of the encircled portion on FIG. 1; FIG. 13 is a detail view of the encircled portion on FIG. 1; and, FIG. 14 is a detail view of the encircled portion on FIG. 2. The line-dot-line broken line that encircles the portions of FIGS. 1-2 and that surrounds the detail views on FIGS. 10-14 forms no part of the claimed design.

1 Claim, 14 Drawing Sheets
